US00D607708S

(12) **United States Design Patent**
Himbert et al.

(10) **Patent No.:** **US D607,708 S**
(45) **Date of Patent:** **** Jan. 12, 2010**

(54) **FILE HANDLE**

(75) Inventors: **Hans Himbert**, Stockholm (SE); **Oskar Juhlin**, Gustavsberg (SE)

(73) Assignee: **Kapman AB**, Sandviken (SE)

(**) Term: **14 Years**

(21) Appl. No.: **29/309,865**

(22) Filed: **Oct. 29, 2008**

(30) **Foreign Application Priority Data**

Oct. 3, 2008 (EM) 001014112

(51) **LOC (9) Cl.** **08-05**

(52) **U.S. Cl.** **D8/107**

(58) **Field of Classification Search** ..... D8/20-29, D8/55, 61, 93, 98-100, 102-107, 300, 301, D8/303, 307, 310, 312, 319-320, 376-378, D8/400-499; D4/132-138; D7/393, 395, D7/401.1, 401.2, 649, 695; D22/104, 118, D22/207; D24/207; D6/524; D26/154; D9/443; 15/143.1, 159.1, 160, 168, 175, 15/194.1, 192; 81/177.1-177.9, 489, 3.2, 81/436, 439-440, 60-63.2, 477, 479, 52; 16/427, 422, 436, 110.1, 421, 430-431, 429, 16/441, 124.6, 414, 417, DIG. 12, DIG. 18, 16/DIG. 19; 73/862.23; 30/164.5, 151-162; 211/87.01; 428/28
